LIQUID FUEL

Arthur A. Roberts, London, England; Arthur Roberts and Clifford Wilbur Smith administrators of said Arthur A. Roberts, deceased

No Drawing. Application July 17, 1934, Serial No. 735,711. Renewed January 11, 1937. In Great Britain June 23, 1933

3 Claims. (Cl. 44—3)

The present invention relates to improvements in liquid or mobile fuels, such as oil or stabilized mixtures of carbonaceous materials, such as coal with oil.

5 It is normally not possible to consume oil or coal-oil mixtures having a water content, as the free water is apt to extinguish the flame.

According to the present invention water is added to a mobile or liquid fuel by emulsification therewith, whereby efficient combustion can be obtained and moreover, it has been found that under certain conditions the intensity of combustion is increased.

10 Various emulsifying agents may be used, such as starch or casein. Either an oil soluble or a water soluble emulsifying agent or both conjointly may be used, such as a sulphonic acid derived from a vegetable oil or a naphthenic acid.

15 Where the fuel is to be used, for instance, in marine work, it will be desirable to use an emulsifier which will operate in the presence of salt or solutions of electrolytes, so that the water content of the fuel will be maintained in emulsification with the fuel in spite of accidental association of the fuel with sea-water or condensed steam.

20 In the application of the invention to coal-oil mixtures or the like the water may conveniently be added as part of the stabilizer for the suspension of the coal particles in the oil where such is employed.

25 Combustion controlling agents, such as boron compounds, may be added and these, if water soluble, may be dissolved in the water addition to the fuel. If desired, non-soluble combustion catalysts, such as one of the oxides of iron may be added to the fuel by suspension therein by means of a stabilizing agent which in coal-oil mixtures may be the same stabilizing agent as used for the coal particles.

30 Intimate emulsification may be obtained by passing the oil with water, or coal dust with oil and water, through a mill, preferably a high speed attrition mill, or a number of such mills in series, which in the case of a coal-oil fuel may also serve to reduce the coal particles to finer size.

35 In the case of a coal-oil fuel the coal may be subjected to grinding with water as a preliminary step prior to treatment for removal of ash forming constituents by any known system, such as for instance, by means of a centrifuge but preferably by a froth flotation process. By this means a substantially ash-free fuel can be obtained which has a high water content, and yet

can be used to form a stable liquid fuel; both solid and water content remain in suspension over any desired storage period.

40 As the addition of water to the oil, or to the coal-oil stabilized mixture by this method will normally tend to increase its viscosity it will, in certain cases, be desirable to reduce the viscosity so that it may be effectively conveyed and consumed. For this purpose materials may be added, such as naphthiaine.

45 By reason of the intimate distribution by means of emulsification of the water throughout the mobile fuel, it will be found that where the fuel is being consumed in a burner this will remain clean, as the dissociation of the water will prevent the partial combustion of the hydrocarbons of the oil or coal and thus prevent the deposit of coke on the burner.

50 It has been found that the efficiency of combustion is remarkably increased by the addition of water to oil or oil-coal stabilized mixtures according to the present invention, as the following comparative tests, taken purely by way of example, will show.

55 A single flue boiler having a rated capacity of 3,000 to 3,500 lbs. of steam per hour and roughly 12 ft. 6 ins. by 6 ft. in size was fired with untreated petroleum oil having a viscosity of 500 seconds on a No. 1 Redwood viscometer.

Specific gravity at 60° Fahrenheit	947	25
Flash point	190° Fahrenheit	
Viscosity at 100° Fahrenheit		
heft	480	35
Ash	0.08%	
Hard asphalt	3.3%	
Water	0.15%	
Coke (Conradson)	8.7%	
Sediment	0.22%	
Sulphur	1.07%	
Cold test	10° Fahrenheit	
Calorific value	18,900 British thermal units per pound	
Duration of test 9 P. M. to 4 A. M.	7 hours	45
Quantity of water evaporated	4660-3566 gallons	
Temperature of feed water	51° Fahrenheit	50
Weight of water used	10940 pounds weight	
Pounds of steam generated	1563 pounds weight	
Quantity of oil consumed	86.0-42 inches	55

Capacity of tank	1"-2547 gallons
Average temperature of oil	180° Fahrenheit
Specific gravity of oil	0.947
5 Specific gravity of oil at 180° Fahrenheit	0.899
Weight of oil used	1008 pounds weight
Calorific value of oil	18,900 per pound weight
10 Weight of water evaporated per pound oil	10.86 pounds
Evaporation from and at 212° Fahrenheit	13.03 pounds
Steam pressure of boiler	100 lbs./sq. in gauge
15 Total heat used per lb. steam	1189 British thermal units
Corrected figure with feed water at 31°	
20 Fahrenheit	1170 British thermal units
British thermal units used in generating	
10.86 pounds weight	
25 steam	12076.2
Actual efficiency at 51° Fahrenheit	12076.2/18900=67.2%
30 The CO ₂ content of the flue gases was practically constant throughout the run and varied from 11% to 12% except for the few minutes occupied in changing the burners.	
The average mean temperature throughout the test was 1280° centigrade.	
35 An oil emulsified with 4% of water using one-eighth of 1% of starch as emulsifier was then consumed under identical conditions with the following result:—	
40 Duration of test	6 hours (10.30 P. M.—6.30 P. M.)
Quantity of water evaporated	12825-11255 gallons
Temperature of feed water	57° Fahrenheit
45 Weight of water used	15700 pounds
Weight of steam generated/hour	1962 pounds
Quantity of oil consumed	80-17,375"
50 Capacity of tank	1"-2.5478 gallons
Average temperature of oil	140° Fahrenheit
Specific gravity of oil	.907 at 161° Fahrenheit
Specific gravity of oil	907 at 161° Fahrenheit
55 Weight of oil used	1440.5 pounds
Weight of water evaporated per pound of oil	10.9 pounds
Steam gauge pressure	94 pounds per square inch
60 Evaporation from/and at 212° Fahrenheit	13.00
Calorific value of fuel	16,710 British thermal units/pound
Total heat used per pound steam	1188 British thermal units
65 Corrected with feed water at 64° Fahrenheit	1163 British thermal units
British thermal units used in evaporating	
10.9 lbs. water	12,676
Actual efficiency	67.7%
70 75 CO ₂ in flue gases	10%

The average mean temperature was found throughout this test to be 1300° centigrade. Moreover, it was found that, while with the untreated or dry oil it was necessary to clean the burners every four hours owing to the considerable quantity of coke deposit forming beneath the flame, with the burners using the treated oil, that is to say, the oil containing the water, only about half the amount of coke deposit had accumulated on the burners after six hours, as compared with the previous accumulation in four hours.

A third test under identical conditions was effected with the same basic medium; that is to say, Anglo-American Petroleum oil having a viscosity of 500 seconds on No. 1 Redwood viscometer, four parts of water being added emulsified by means of one eighth of one part of starch together with three eighths of one part of borax or boric acid in solution in the water and three eighths of one part of sodium chloride in solution in the water, per hundred parts by weight of oil.

It may here be stated that sodium chloride whilst normally acting as a combustion retarding agent is believed to have a retarding effect solely upon the rate of combustion, whilst the boron compound addition has a remarkable effect in increasing the intensity of combustion. This test has had as a result:—

Duration of test	4 hours 3 p. m. to 7 p. m.
Quantity of water evaporated	18703-17908 gallons
Temperature of feed water	60° Fahrenheit
Weight of water used	7950 pounds
Weight of steam generated/hour	19875 pounds
Quantity of oil consumed	29.36"
Capacity of oil tank	1"-2.5478 gallons
Average temperature of oil	140° Fahrenheit
Weight of oil used (Sp. Gr.-912 at 140° Fahrenheit)	683.5 pounds
Weight of water evaporated per pound oil	11.63 pounds
Steam gauge pressure	90 pounds
Evaporation from and at 212° Fahrenheit	13.89
Calorific value of dry fuel	18,900
Calorific value of dry fuel plus 4% water	18,144
Total heat used per pound steam British thermal units used in converting	11.63
pounds water	13,491
Actual efficiency	74.35%

The average mean temperature was 1320° centigrade.

It can readily be ascertained that similar tests with stabilized coal-oil mixtures having a water content and stabilized coal-oil mixtures having a water content together with combustion promoting agents would give similar results in increase in efficiency.

Satisfactory combustion has been obtained with oil and oil-coal stabilized mixtures with the water content as high as 10%, although in such cases the combustion efficiency would not be as high as with a lower water content. It will however, be

appreciated that a considerably cheaper fuel can be obtained by this means giving equivalent efficiency to an untreated oil with the additional advantages of burner cleanliness in operation.

5 Fuels manufactured according to the present invention will also be suitable for use in internal combustion engines, for instance, of the self-ignition type.

I declare that what I claim is:—

10 1. A liquid fuel comprising an emulsion of fuel oil with water, said water component having dissolved therein a compound of the group consisting of boric acid and water-soluble borates for controlling the combustion and said water component also having therein an emulsifying and stabilizing agent of the group consisting of starch and casein and characterized by being operative in the presence of electrolytes.

15 2. A liquid fuel comprising an emulsion of fuel

oil with water, said water component having dissolved therein boric acid for controlling the combustion and an emulsifying and stabilizing agent of the group consisting of starch and casein and characterized by being operative in the presence 5 of electrolytes.

3. A liquid fuel comprising an emulsion of fuel oil with substantially 4% of water, said water component having dissolved therein a water-soluble boron-oxygen compound for controlling 10 the combustion and an emulsifying agent of the group consisting of starch and casein and characterized by being operative in the presence of electrolytes, the total quantity of boron-oxygen compound and emulsifying agent being substantially one-half of 1% by weight of the emulsion, and particles of powdered coal suspended in the emulsion. 15

ARTHUR A. ROBERTS.
